WARP KNITTING MACHINE

Fritz Lambach, Tenafly, N. J., assignor to
Robert Reiner, Inc., Weehawken, N. J.

Application March 17, 1948, Serial No. 15,320

24 Claims. (Cl. 66—149)

1

The present invention relates to textile machines, and more particularly to warp knitting machines.

An object of the present invention is to provide a warp knitting machine with a take-up mechanism wherein the take-up roller is readily accessible for removal of the finished knitted fabric.

Another object of the invention is to equip a warp knitting machine of the type having two banks of needles with an automatic take-up mechanism for taking up the fabric knitted by the knitting implements of the warp knitting machine.

A further object of the invention is to improve upon the construction of take-up devices for warp knitting machines as now ordinarily made.

With the above and other objects of the invention in view, the invention consists in the novel construction, arrangement and combination of various devices, elements and parts, as set forth in the claims hereof, an embodiment of the same being described in the specification and being illustrated in the accompanying drawings, forming part of this specification, wherein:

Fig. 1 is a more or less diagrammatical front elevational view of a warp knitting machine according to the invention.

Fig. 2 is a sectional view of the warp knitting machine shown in Fig. 1 taken on line 2—2 of Fig. 1.

Fig. 3 is a fragmentary sectional view of the warp knitting machine similar to the sectional view shown in Fig. 2, however, in an enlarged scale.

Fig. 4 is a vertical sectional view of the warp knitting machine taken on line 4—4 of Fig. 3.

Fig. 5 is a sectional view taken on line 5—5 of Fig. 4.

Fig. 6 is a fragmentary sectional view similar to the sectional view shown in Fig. 3, wherein, however, the take-up roller is disengaged from the take-up drive proper, and

Fig. 7 is a fragmentary perspective view illustrating a connection of the take-up roller with a shaft journalled in a bearing of the support carrying the take-up roller.

The drawings illustrate only those parts of a warp knitting machine, which are necessary for the understanding of the invention.

In the drawings 20 generally indicates the frame of a so-called "Simplex" warp knitting machine having two banks of warp guides 22, two banks of sinkers 24 and two banks of needles 26 extending longitudinally of the machine.

2

As best shown in Figs. 1 and 2, the frame of the warp knitting machine comprises two end walls 28 and 30 connected with each other by a plurality of girts 32. There are no intermediate walls between said two end walls 28 and 30 so that it is possible to arrange a take-up roller 34 in the machine, in a manner to be described hereinafter, below the level of the banks of needles 26, said take-up roller extending longitudinally of the machine. The girts 32 are of such robust construction and are arranged in such a manner that the frame 20 is sufficiently strong to carry the various elements, parts and devices of the warp knitting machine. In a preferred embodiment, each girt is made of four side plates 36, 38, 40, 42 (see Figs. 1 and 2) welded together so as to form a hollow body of rectangular cross-section; each girt is closed at its ends by head plates 44 welded to the side plates of the girt and provided with threaded bores capable of receiving screws for attaching the girts to the end walls 28, 30.

As best shown in Figs. 1 and 4, a shaft 46 journalled in suitable bearings of the end walls 28 and 30 may be rotated by means of a motor 48 through the medium of a suitable belt-drive 50. Said shaft 46 represents a cam shaft carrying a plurality of cams (not shown in the drawings) pertaining to various actuating devices of the warp knitting machine. A crank 52 rigidly connected with the end of said cam shaft 46 projecting from the end wall 28 is pivotally connected at 54 with the upper end of a connecting rod 56, the lower end of which is pivotally connected at 58 to one end of an arm 60 loosely arranged on a shaft 62 rotatably arranged in a suitable bearing of the end wall 28. The eccentric arrangement of the pivotal connection 54 between the crank 52 and the upper end of the connecting rod 56 is adjustable. Likewise, the length of said connecting rod 56 is adjustable. As best shown in Fig. 5, said arm 60 carries a spring-loaded pawl 64 arranged for engagement with teeth of a ratchet wheel 66 keyed to the shaft 62. Therefore, when, during the operation of the warp knitting machine, the connecting rod 56 is reciprocated by means of the crank 52 driven by the cam shaft 46, the ratchet wheel 66 will be advanced step by step as often as the spring-loaded pawl 64 may find a tooth of the ratchet wheel 66 for cooperation therewith.

The ratchet wheel 66 is held in its position by means of a spring-loaded holding pawl 68 swingably mounted on a bolt 70 secured to the end wall 28.

As best shown in Figs. 3 and 4, two arms 72 and 74 constituting supporting means capable of receiving above mentioned take-up roller 34 are rigidly connected with a shaft 76 journalled in suitable bearings of the end walls 28 and 30. A shaft 78 (see Figs. 4 and 7) is rotatably but axially immovably arranged in the lower end of the arm 72. A gear 80 keyed to the end of said shaft 78 projecting from the right side of the arm 72 (as viewed in Figs. 4 and 7) is in mesh with a pinion 82 keyed to the shaft 62 of the take-up drive described above, when the supporting arm 72 is in the position shown in Fig. 3.

As best shown in Figs. 4 and 7, a carrying block 84 having a bore for receiving the end of the shaft 78 projecting from the left side of the arm 72 is positively coupled with said shaft 78 by means of a pin 86 passing through registering bores of the block 84 and the shaft 78. Said carrying block 84 is provided with a recess 88 capable of receiving a square bar 90 which, in turn, may be passed through a corresponding square aperture of the take-up roller 34.

In a similar manner, a carrying block 92 is secured to a shaft 94 rotatably but axially immovably arranged in a bearing of the supporting arm 74 at the other side of the machine. Said carrying block 92 has a recess 96 capable of receiving the other end of said square bar 90 carrying the take-up roller 34.

The square bar 90 may be held in the recesses 88 and 96 of the carrying blocks 84 and 92 by means of latches 98 swingably mounted on the blocks 84 and 92. As best shown in Fig. 7, for example, the latch 98 swingably mounted at 100 on the block 84 has a slot 102 capable of engagement with the stem of a thumb-screw 104. When the square bar 90 is engaged with the recesses of the carrying blocks, the latches 98 are brought into the position shown in Figs. 4 and 7 wherein the slot 102 of each latch 98 is engaged with the thumb-screw 104. Each thumb-screw 104 is tightened so as to hold the latch 98 in place, whereby the square bar 90 carrying the take-up roller 34 is held in engagement with the carrying blocks 84 and 92.

If it is desired to remove the take-up roller 34 from the supporting arms 72, 74, the thumb-screws 104 are loosened so that the latches 98 may be swung into such a position wherein the square bar 90 may be disengaged from the recesses 88 and 96 of the carrying blocks 84 and 92.

When the machine is in operation, the fabric 106 knitted by the knitting implements 22, 24, 28 of the machine is wound on above described take-up roller 34, which at this time is positively coupled with the pinion 82 of the take-up drive through the medium of the gear 80 keyed to the shaft 78 positively coupled with the carrying block 84 engaged with the square bar 90 carrying the take-up roller 34. The take-up roller 34 is prevented from rotation in clockwise direction (as viewed in Fig. 3) owing to the engagement of the spring-loaded holding pawl 68 with a tooth of the ratchet wheel 66. The fabric 106 is held under tension by means of a tensioning bar 108 carried by arms 110, 112 rigidly secured to a shaft 114 journalled in bearings of the end walls 28 and 30. Furthermore, an arm 116 is rigidly secured to said shaft 114. The movement of said arm 116 is limited by stop screws 118, 120. The arm is provided with a series of holes 122. One end of a tensioning spring 124 may be selectively connected with one hole of said series of holes 122. The other end of said tensioning spring 124 is con-

nected to a bolt 126 secured to the end wall 28. Thus, said spring 124 tends to urge the arm 116 in clockwise direction (as viewed in Fig. 3) whereby the arms 110 and 112 secured to the shaft 114 likewise tend to move in clockwise direction so as to hold the fabric 106 trained around the tensioning bar 108 under tension.

Furthermore, as best shown in Figs. 3, 4 and 5, a lever 128 is rigidly secured to the shaft 114 so as to participate in oscillating movements of the latter. One end of an adjustable connecting rod 130 is pivoted at 132 to said lever 128; the other end of said connecting rod 130 is pivoted at 134 to an arm 136 of a double-armed lever 138 loosely arranged on the shaft 62. As best shown in Fig. 5, the other arm 140 of said double-armed lever 138 is provided with a controlling surface 142 which may cooperate with the spring-loaded actuating pawl 64 swingably mounted on the arm 60 oscillated by above-described take-up drive. When the double-armed lever 138 and the controlling surface 142 are in the position shown in full lines in Fig. 5, the controlling surface 142 is in such a position relative to the actuating pawl 64 that the latter may find one tooth of the ratchet wheel 66 for advancing same one step upon a rocking of the arm 60 in clockwise direction. If, however, during the operation of the warp knitting machine, the tension in the fabric 106 increases and the tensioning bar 108 (see Fig. 3) rigidly connected with the shaft 114 is moved against the action of the spring 124 in counter-clockwise direction, the lever 128 also rigidly secured to the shaft 114 is, likewise, swung in counter-clockwise direction so as to reach the position 128' shown in dash and dot lines in Fig. 5. This movement of the lever 128 into the position 128' in turn results in a movement of the double-armed lever 138 into the position 138' shown in dash and dot lines in Fig. 5. When the double-armed lever is in said position 138', the controlling surface 142 lifts the actuating pawl 64 into the position 64' shown in dash and dot lines in Fig. 5. Now, when the arm 60 is rocked in clockwise direction, the pawl 64 cannot find a tooth of the ratchet wheel 66, so that the latter will not be advanced. As soon as the normal tension in the fabric 106 has been restored and the tensioning rod 108 reaches again the position shown in Fig. 3 by the action of the spring 124, the controlling surface 142 will reach the position shown in full lines in Fig. 5, so that during the next rocking movement of the arm 60 the actuating pawl 64 may again advance the ratchet wheel 66 through one step.

On the other hand, if the tension in the fabric 106 should decrease below the normal degree, the tensioning rod 108 will be swung in clockwise direction by the action of the spring 124 from the position shown in Fig. 3, so that the controlling surface 142 will be swung to the same extent from the position shown in full lines in Fig. 5 in counter-clockwise direction. Such a displacement of the controlling surface 142 permits the engagement of the actuating pawl 64 with such a tooth of the ratchet wheel 66 that the latter will be advanced through two steps, for example. As soon as by such an increased advancement of the ratchet wheel 66 driving the take-up roller 34 through the medium of the pinion 82 and gear 80 the normal tension in the fabric 106 has been restored, the tensioning rod 108 will again reach the position shown in Fig. 3 and the controlling surface 142 will be returned into the position shown in full lines in Fig. 5.

As will be readily understood from above, the take-up drive for rotating the take-up roller through the medium of the coupled pinion 82 and gear 80 is equipped with means responsive to the tension in the fabric.

In accordance with the invention, the position of the take-up roller 34 extending longitudinally of the machine along a longitudinal side thereof may be changed by the following positioning means: As best shown in Figs. 3, 4 and 6, a worm gear 144 rigidly secured to the shaft 76 rigidly connected with the movable arms 72 of the support carrying the take-up roller 34 is in mesh with a worm 146 rotatably and axially immovably arranged in suitable bearings 148 mounted on the end wall 28.

Preferably, said worm 146 is of the self-locking type. A hand wheel 150 is rigidly connected with the shaft carrying the worm 146, so that the latter may be rotated by hand. Moreover, an index wheel 152 is rigidly connected with the shaft carrying the worm 146. A detent made of resilient material 154 is arranged on the machine for cooperation with the teeth of the index wheel 152, so as to hold the worm 146, the worm gear 144 and the arms 72, 74 of the support carrying the take-up roller 34 in an adjusted position.

The extreme position of the support 72, 74, wherein the gear 80 is coupled with the pinion 82 of the take-up drive, is limited by an abutment of adjustable stop screws 156 arranged on the arms 72 and 74 against a girt 32 as best shown in Fig. 3.

When the take-up roller 34 is fully loaded, the warp knitting machine is stopped. Thereupon, the support 72, 74 carrying the take-up roller 34 may be swung by means of the positioning mechanism 144-150 from the position shown in Fig. 3 into the position shown in Fig. 6, wherein the gear 80 is disengaged from the pinion 82. In said position, the take-up roller 34 with the fabric wound thereon is substantially outside the frame 20 of the warp knitting machine and is readily accessible to the operator of the machine. Thus, the fabric may be readily cut, whereupon the full take-up roller may be removed from the swingable support 72, 74 and may be replaced by an empty one.

After insertion of the empty take-up roller 34 into the support 72, 74, the latter may be returned by means of the positioning mechanism 144-150 into the position shown in Fig. 3 wherein the gear 80 is engaged with the pinion 82 of the take-up drive. The free end of the fabric is attached to the take-up roller 34 in any suitable manner and the warp knitting machine is restarted. During the subsequent operation of the machine, the fabric is again wound on the take-up roller 34 by means of above-described drive.

I have described a preferred embodiment of my invention, but it is understood that numerous changes and omissions may be made without departing from the spirit and scope of the invention set forth in the appended claims.

What I claim is:

1. In a warp knitting machine, the combination of: a frame comprising a pair of connected end walls spaced from each other, supporting means movably mounted on the frame of the machine, a take-up roller rotatably arranged on said movable supporting means for rotation about a fixed axis, said take-up roller extending longitudinally of the machine and being normally

in the space between said end walls of the frame, said supporting means being movable so as to bring said take-up roller from its normal position in the space between said end walls into a temporary position at least partially outside the frame of the machine, a positioning mechanism associated with said movable supporting means for bringing same into alternative positions, and a take-up drive associated with said take-up roller for positively rotating same.

2. In a warp knitting machine, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame, said supporting means being movable so as to bring said take-up roller from its normal position in the space between said end walls into a temporary position at least partially outside the frame of the machine, a positioning mechanism associated with said movable supporting means for bringing same into alternative positions, a take-up drive arranged on the frame of the machine, and disengageable coupling means associated with said take-up drive and said take-up roller, said coupling means being in positively engaged condition when said take-up roller is in its normal position and being in disengaged condition when said take-up roller is in a temporary position.

3. In a warp knitting machine, the combination of: a take-up drive arranged on the knitting machine, a first coupling element included in said take-up drive, a support movably arranged on the knitting machine, a second coupling element rotatably mounted on said support and capable of positive engagement with said first coupling element, said support being capable of receiving a take-up roller for positive connection thereof with said second coupling element, and a positioning mechanism associated with said movable support for bringing same into alternative positions and thus bringing the second coupling element into and out of engagement with said first coupling element.

4. In a warp knitting machine, the combination of: a take-up drive arranged on the knitting machine, a first coupling element included in said take-up drive, a support movably arranged on the knitting machine, a second coupling element rotatably mounted on said support, a take-up roller rotatably and exchangeably arranged on said support, disengageable connecting means associated with said take-up roller and said second coupling element for positively connecting same with each other, and a positioning mechanism associated with said movable support for bringing same into alternative positions and thus bringing the second coupling element into and out of engagement with said first coupling element.

5. In a warp knitting machine, the combination of: a take-up drive arranged on the knitting machine, a pinion included in said take-up drive, a support movably arranged on the knitting machine, a gear rotatably mounted on said support, said support being capable of receiving a take-up roller for positive connection thereof with said gear, and a positioning mechanism associated with said movable support for bringing same into alternative positions and thus bringing said gear into and out of mesh with said pinion.

6. In a warp knitting machine having knitting

implements for knitting a fabric, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame for receiving fabric knitted by the knitting implements of the machine, a take-up drive arranged on the frame of the machine, disengageable coupling means associated with said take-up drive and said take-up roller, said coupling means being in positively engaged condition when said take-up roller is in its normal position whereby said take-up drive may rotate said take-up roller, said take-up drive including means for intermittently rotating said take-up roller, means responsive to the tension in the fabric associated with said take-up drive for adjusting the degree of its intermittent rotating of the take-up roller, said supporting means being movable so as to bring said take-up roller from its normal position into a temporary position at least partially outside the frame of the machine wherein said coupling means are in disengaged condition, and a positioning mechanism associated with said movable supporting means for bringing same into alternative positions.

7. In a warp knitting machine, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame, said supporting means being movable so as to bring said take-up roller from its normal position in the space between said end walls into a temporary position at least partially outside the frame of the machine, a positioning mechanism associated with said movable supporting means for bringing same into alternative positions, holding means associated with said supporting means for holding same in a predetermined position, and a take-up drive associated with said take-up roller for positively rotating same.

8. In a warp knitting machine, the combination of: a frame comprising a pair of connected end walls spaced from each other, supporting means swingably mounted on the frame of the machine, a take-up roller rotatably arranged on said swingable supporting means, said take-up roller extending longitudinally of the machine and being normally in the space between said end walls of the frame, said supporting means being swingable so as to bring said take-up roller from its normal position in the space between said end walls into a temporary position at least partially outside the frame of the machine, a positioning mechanism associated with said swingable supporting means for bringing same into alternative positions, and a take-up drive associated with said take-up roller for positively rotating same, said take-up drive and said supporting means being separate units, and said supporting means being movable away from and toward said take-up drive.

9. In a warp knitting machine, the combination of: a take-up drive arranged on the knitting machine, a first coupling element included in said take-up drive, a support swingably mounted

on the knitting machine, a second coupling element rotatably mounted on said support, said support being capable of receiving a take-up roller for positive connection thereof with said second coupling element, and a positioning mechanism associated with said swingable support for bringing same into alternative positions and thus bringing the second coupling element into and out of engagement with said first coupling element.

10. In a warp knitting machine, the combination of: a take-up drive arranged on the knitting machine, a first coupling element included in said take-up drive, a support swingably mounted on the frame of the machine, a second coupling element rotatably mounted on said support and capable of positive engagement with said first coupling element, a take-up roller rotatably and exchangeably arranged on said support, disengageable connecting means associated with said take-up roller and said second coupling element for positively connecting same with each other, and a positioning mechanism associated with said swingable support for bringing same into alternative positions and thus bringing the second coupling element into and out of engagement with said first coupling element.

11. In a warp knitting machine, the combination of: a take-up drive arranged on the knitting machine, a first coupling element included in said take-up drive, a support swingably mounted on the knitting machine, a second coupling element rotatably mounted on said support, said support being capable of receiving a take-up roller for positive connection thereof with said second coupling element, and a manual positioning mechanism associated with said swingable support for bringing same into alternative positions and thus bringing the second coupling element into and out of engagement with said first coupling element.

12. In a warp knitting machine, the combination of: a take-up drive arranged on the knitting machine, a first coupling element included in said take-up drive, a support swingably mounted on the knitting machine, a second coupling element rotatably mounted on said support and capable of positive engagement with said first coupling element, said support being capable of receiving a take-up roller for positive connection thereof with said second coupling element, a positioning mechanism associated with said swingable support for bringing same into alternative positions and thus bringing the second coupling element into and out of engagement with said first coupling element, and holding means associated with said swingable support for holding same in a position set by said positioning means.

13. In a warp knitting machine as claimed in claim 11, said positioning mechanism including a worm and a worm gear operatively engaged with each other, said worm gear being connected to said swingable support, and actuating means connected to said worm gear for actuating same.

14. In a warp knitting machine as claimed in claim 11, said positioning mechanism including a worm and a worm gear operatively engaged with each other, said worm gear being connected to said swingable support, actuating means connected to said worm gear for actuating same, an index wheel positively coupled with said positioning mechanism, and a loaded element arranged for cooperation with said index wheel so as to hold same and the support in a position set by said positioning mechanism.

15. In a warp knitting machine, the combination of: a take-up drive arranged on the knitting machine, a first coupling element included in said take-up drive, a support swingably mounted on the knitting machine, a second coupling element rotatably mounted on said support, said support being capable of receiving a take-up roller for positive connection thereof with said second coupling element, a positioning mechanism associated with said swingable support for bringing same into alternative positions and thus bringing the second coupling element into and out of engagement with said first coupling element, and limiting means associated with said swingable support for limiting its extreme position wherein said coupling elements are engaged with each other.

16. In a warp knitting machine, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame, said supporting means being movable so as to bring said take-up roller from its normal position in the space between said end walls into a temporary position at least partially outside the frame of the machine, a positioning mechanism associated with said movable supporting means for bringing same into alternative positions, a take-up drive associated with said take-up roller for rotating same, and means associated with said take-up drive and said take-up roller for maintaining a predetermined ratio of revolution between same during the operation of the machine.

17. In a warp knitting machine, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame, said supporting means being movable so as to bring said take-up roller from its normal position in the space between said end walls into a temporary position at least partially outside the frame of the machine, a positioning mechanism associated with said movable supporting means for bringing same into alternative positions, a take-up drive arranged on the frame of the machine, disengageable coupling means associated with said take-up drive and said take-up roller, said coupling means being in engaged condition when said take-up roller is in its normal position and being in disengaged condition when said take-up roller is in a temporary position, and said coupling means being arranged for maintaining a predetermined ratio of revolution between same when they are in engaged condition during the operation of the machine.

18. In a warp knitting machine, the combination of: a take-up drive arranged on the knitting machine, a first coupling element included in said take-up drive, a support movably arranged on the knitting machine, a second coupling element rotatably mounted on said support, said support being capable of receiving a take-up roller for positive connection thereof with said second coupling element, and a positioning mechanism associated with said movable support for

bringing same into alternative positions and thus bringing the second coupling element into and out of engagement with said first coupling element, and said first and second coupling elements being arranged for maintaining a predetermined ratio of revolution between same when they are in engagement with each other during the operation of the machine.

19. In a warp knitting machine having knitting implements for knitting a fabric, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame for receiving fabric knitted by the knitting implements of the machine, a take-up drive arranged on the frame of the machine, disengageable coupling means associated with said take-up drive and said take-up roller, said coupling means being in engaged condition when said take-up roller is in its normal position whereby said take-up drive may rotate said take-up roller, said coupling means being arranged for maintaining a predetermined ratio of revolution between same when they are in engaged condition during the operation of the machine, said take-up drive including means for intermittently rotating said take-up roller, means responsive to the tension in the fabric associated with said take-up drive for adjusting the degree of its intermittent rotating of the take-up roller, said supporting means being movable so as to bring said take-up roller from its normal position into a temporary position at least partially outside the frame of the machine wherein said coupling means are in disengaged condition, and a positioning mechanism associated with said movable supporting means for bringing the same into alternative positions.

20. In a warp knitting machine, the combination of: a frame comprising a pair of connected end walls spaced from each other, supporting means movably mounted on the frame of the machine, a take-up roller rotatably arranged on said movable supporting means, said take-up roller extending longitudinally of the machine and being normally in the space between said end walls of the frame, said supporting means being movable so as to bring said take-up roller from its normal position in the space between said end walls into a temporary position at least partially outside the frame of the machine, a positioning mechanism associated with said movable supporting means for bringing same into alternative positions, holding means associated with said supporting means for holding same in a predetermined position, a take-up drive associated with said take-up roller for rotating same, and means associated with said take-up drive and said take-up roller for maintaining a predetermined ratio of revolution between same during the operation of the machine.

21. In a warp knitting machine, the combination of: a frame comprising a pair of connected end walls spaced from each other, supporting means swingably mounted on the frame of the machine, a take-up roller rotatably arranged on said swingable supporting means, said take-up roller extending longitudinally of the machine and being normally in the space between said end walls of the frame, said supporting means being swingable so as to bring said take-up roller

from its normal position in the space between said end walls into a temporary position at least partially outside the frame of the machine, a positioning mechanism associated with said swingable supporting means for bringing same into alternative positions, a take-up drive associated with said take-up roller for rotating same, and means associated with said take-up drive and said take-up roller for maintaining a predetermined ratio of revolution between same during the operation of the machine.

22. In a warp knitting machine, the combination of: a take-up drive arranged on the knitting machine, a first coupling element included in said take-up drive, a support swingably mounted on the knitting machine, a second coupling element rotatably mounted on said support, said support being capable of receiving a take-up roller for positive connection thereof with said second coupling element, a positioning mechanism associated with said swingable support for bringing same into alternative positions and thus bringing the second coupling element into and out of engagement with said first coupling element, said first and second coupling elements being arranged for maintaining a predetermined ratio of revolution between same when they are in engagement with each other during the operation of the machine, and holding means associated with said swingable support for holding same in a position set by said positioning means.

23. In a warp knitting machine, the combination of: a frame comprising a pair of connected end walls spaced from each other, a bank of needless extending longitudinally of the machine, supporting means movably mounted on the frame of the machine, a take-up roller rotatably arranged on said movable supporting means, said take-up roller extending longitudinally of the machine and being normally in the space between said end walls of the frame and below the level of said bank of needles, said supporting means being movable so as to bring said take-up roller from its normal position in the space between said end walls into a temporary position at least partially outside the frame of

the machine, a positioning mechanism associated with said movable supporting means for bringing same into alternative positions, and a take-up drive associated with said take-up roller for positively rotating same.

24. In a warp knitting machine, the combination of: a frame comprising a pair of connected end walls spaced from each other, a bank of needless extending longitudinally of the machine, supporting means movably mounted on the frame of the machine, a take-up roller rotatably arranged on said movable supporting means for rotation about a fixed axis, said take-up roller extending longitudinally of the machine and being normally in the space between said end walls of the frame and below the level of said bank of needles, said supporting means being movable so as to bring said take-up roller from its normal position in the space between said end walls into a temporary position at least partially outside the frame of the machine, a positioning mechanism associated with said movable supporting means for bringing same into alternative positions, and a take-up drive associated with said take-up roller for positively rotating same.

FRITZ LAMBACH.
